EUGENE ST. PIERRE,
By Roy T. Lovell,
ATT'Y.

UNITED STATES PATENT OFFICE

2,278,904

KNITTED FABRIC

Eugene St. Pierre, Pawtucket, R. I., assignor to
Hemphill Company, Central Falls, R. I., a corporation of Massachusetts

Original application December 19, 1938, Serial No.
246,580. Divided and this application September
6, 1940, Serial No. 355,699

5 Claims. (Cl. 66—172)

This case involves a method of knitting and a stocking top in which an elastic yarn is incorporated along with a so-called plain yarn or yarns.

This application is a division of co-pending application Serial No. 246,580, filed December 19, 1938, now Patent #2,246,194.

In the figures of drawing:

Fig. 1 is an elevation showing a half hose in which a top is conventionally shown knitted in accordance with the invention; and

Fig. 2 is a conventional view of a section of fabric, greatly enlarged, and showing several courses at the beginning of the stocking top.

In knitting simulated rib stocking tops with elastic yarn incorporated therein for rendering the stocking self-supporting and for other purposes, the initial course commonly has an elastic yarn passing through certain loops such as through the sinker loops, for example, to render the edge fast against ravelling. A common difficulty experienced with these tops is that they flare outwardly tending to curl at the topmost portion and in some instances, do not present the most pleasing or satisfactory appearance.

As described in the present case, the elastic yarn is incorporated in accordance with one form of the invention, by knitting the same at an auxiliary feed and on every other needle. A plain or non-elastic yarn, so-called, is to be knitted at a second feeding station and will, throughout the greater part of the stocking top, be knitted on all needles or in all wales. However, if for the first few courses the said plain yarn is tucked on certain needles as on intermediate needles, it has been found that a more satisfactory top will result, both from the point of view of appearance and stretch characteristics, and that furthermore, the edge will be more resistant to curling than if constructed in accordance with principles heretofore prevailing.

While not necessarily being knitted on a machine having two separate feeding stations, one preferred form of the invention will be practiced by employing a machine having a main feeding station, an auxiliary feeding station and jacks under alternate needles and butt selection by means of which those needles may be raised to a yarn taking and latch clearing position at the auxiliary feeding station. At that station a knitting cam will draw needles through a path satisfactory for purposes of stitch drawing. At the main feeding station the usual cams are to be employed and the front stitch cam is to be capable of moving to inactive position at desired

times. A similar jack selecting or needle dividing cam functions in advance of the front stitch cam and raises needles individual to the jacks to a clearing and incidentally a yarn taking position.

Probably the best way of describing the characteristics of the top and method of producing the same is to explain the manner in which each individual course of the fabric, Fig. 2, is constructed and the operation of the machine incidentally thereto. In Fig. 1, a stocking is illustrated having a top 1 with a selvage 2, a leg 3, foot 4, and heel and toe 5 and 6, respectively. The top is preferably knitted to simulate a rib appearance and to provide sufficient elasticity for garter purposes in accordance with the method disclosed in United States Patent #2,131,720. The beginning edge which involves the first few courses is to be constructed in accordance with what is illustrated in Fig. 2 and not described in this case.

At the start of knitting no yarn is being fed at the main feeding station and at the auxiliary feed, an elastic yarn is to be fed for two courses and to alternate needles. The needles are to be raised for taking this elastic yarn by selection involving jacks and a dividing cam as above explained, and as more thoroughly described in the patent mentioned above and in co-pending application Serial #243,914, filed December 5, 1938, now Patent #2,248,875. Intermediate needles do not rise to a height sufficient to take this elastic yarn. The elastic yarn indicated at 7 will be temporarily drawn into loops in course A, but since there were no previously drawn loops on the needles and since no yarn is fed at the main side of the machine, needles will rise above the front stitch cam, clearing the latches, and as they pass under the back stitch cam, will knit off the elastic just taken. On the second revolution of the machine those same needles will take the elastic yarn again as in the course illustrated at B, and prior to reaching the main side of the machine, a so-called plain yarn such as cotton, silk or the like will be thrown into action; also, the needle dividing cam or jack cam at that side of the machine will move in to butt engaging position while the front stitch cam will be withdrawn. At that side of the machine, all needles will be moved high enough to take yarn, but only alternate needles will clear their latches. The result of this is that alternate needles will draw loops of plain yarn 8 through the elastic yarn loops just drawn at the auxiliary side. The intermediate needles will take yarn, but since

there was nothing on those needles it will not be drawn through other stitches. This constitutes the knitting of course C. The machine set up now remains the same and in another revolution, course D is knitted comprising elastic yarn loops drawn at the auxiliary side and through the last drawn plain yarn loops 8. The intermediate needles do not take the elastic as before, but merely retain their loops 9 of plain yarn.

At the main side course E will be knitted similar to course C, the alternate needles drawing loops through the elastic at that side while the intermediate needles take other loops 10 in addition to the loops 9 already held. In the next revolution of the machine elastic yarn is again taken by the alternate needles at the auxiliary side, is knitted, and the last drawn plain yarn stitches are cast off. This course is shown at F. The machine makes another move at this time and the front stitch cam will move to active position while the jack cam at that side may be withdrawn. Course G will be knitted from the plain yarn, all needles taking the yarn and immediately drawing loops therefrom. At this time, the front stitch cam will resume its usual function of clearing all needles prior to their taking yarn so that the accumulated loops 9 and 10 will be knitted off as other plain yarn loops are drawn through them.

From this point courses are knitted wherein the elastic is fed at the auxiliary side, knitting on every other needle while the plain yarn feeds at the main side and knits on every needle. This is in accordance with the disclosure in United States Patent #2,131,720 and the remaining fabric 30 throughout the top may be knitted in this fashion.

While the fabric in Fig. 2 is conventionally shown so that a clear understanding of the manner of knitting may be gained, it is to be understood that the elastic is fed under some tension and that elastic loops tend to draw up or contract to a certain degree. This results in imparting a rib appearance to the fabric as disclosed in the said patent. The first course of elastic A which was cast from the needles will be cut away and course B, when contracted, will appear as threaded through sinker loops of the first plain course C. The edge of the fabric is greatly strengthened

5 by the plain yarn tuck loops and tends to remain straight rather than to flare or curl. The fact that knitting the elastic into individual stitches and that the elastic is knitted under a slight tension results in a fabric which is not excessively tight so that the few courses at the beginning edge in which tuck stitches are knitted serve very effectively to maintain the edge straight and to prevent curling. The tuck stitches as shown constitute two held loops. It is to be understood that the tuck may be varied and that in some instances more or a lesser number of held loops may be used. The invention is to be limited only by the scope of the appended claims.

I claim:

1. A selvage for a plain knitted (not rib) fabric including an edge fast against ravelling, elastic yarn incorporated to be held at alternate wales only and a plain yarn knitted in said alternate

20 wales but tucked at intermediate wales.

2. A selvage for a plain knitted (not rib) fabric including an edge fast against ravelling, elastic yarn knitted in alternate wales, a plain yarn knitted through said elastic yarn loops in alternate wales, but drawn into tuck stitches at intermediate wales.

25 3. A selvage for a knitted fabric having in combination an elastic and a plain yarn knitted alternately, said elastic yarn being knitted only in alternate wales and said plain yarn being knitted in alternate wales and tucked in intermediate wales.

4. A selvage for a plain knitted (not rib) fabric including an edge fast against ravelling, elastic and non-elastic yarns, the non-elastic yarn being knitted at alternate wales and tucked at intermediate wales over a plurality of courses, and the elastic yarn being held at non-adjacent knitted wales only in some of said courses.

40 5. A selvage for a plain knitted (not rib) fabric including an edge fast against ravelling, elastic and non-elastic yarns, the non-elastic yarn being knitted at alternate wales in a plurality of courses and being tucked at intermediate wales therein, the said elastic yarn being held against lateral displacement at said alternate wales only and being floated over said intermediate tuck wales.

EUGENE ST. PIERRE.
